(57) **CLAIM**

The ornamental design for an eye testing apparatus and equipment as shown and described.

DESCRIPTION

FIG. 1 is a top, front, and right side perspective view of an eye testing apparatus and equipment showing our new design;

FIG. 2 is a bottom, front, and right side perspective view thereof;

FIG. 3 is a bottom, back, and left side perspective view thereof;

FIG. 4 is a front view thereof;

FIG. 5 is a back view thereof;

FIG. 6 is a top plan view thereof;

FIG. 7 is a bottom plan view thereof;

FIG. 8 is a right side elevational view thereof;

FIG. 9 is a left side elevational view thereof; and,

FIG. 10 is a reference view showing the eye testing apparatus and equipment in an alternate position.

In the drawings, the broken lines depict portions of the eye testing apparatus and equipment that form no part of the claimed design.

1 Claim, 10 Drawing Sheets
